FIG. 1

FIG. 2

FIGURE 1 is a front, right and top perspective view of a cabinet for an output printer unit showing our new design.

FIGURE 2 is a rear, left and top perspective view of the design of FIGURE 1.

The characteristic feature of our design resides in the appearance and arrangement of the several panels forming the front thereof as best shown in FIGURE 1.

The grill work on the top is continuous across the entire surface.

We claim:

The ornamental design of a cabinet for an output printer unit, substantially as shown and described.
